CHANCE TYPE AMUSEMENT DEVICE

Philip J. Rowman, Hillsboro Park, Derry Road,
Hudson, N.H. 03051

Filed June 4, 1973, Ser. No. 366,413

Term of patent 14 years

Int. Cl. D21—01
U.S. Cl. D34—5 MM

Fig. 1.

Fig. 2.

Fig. 3.

Fig. 4.

Fig. 5.

FIG. 1 is a top plan view of a chance type amusement device, embodying my new design;

FIG. 2 is a front elevational view thereof;

FIG. 3 is a side elevational view of the chance type amusement device, the other side being identical;

FIG. 4 is a bottom plan view; and

FIG. 5 is a perspective view of the device, the portions of the side wall not shown being smooth and cylindrical. The numerals seen are representative.

I claim:

The ornamental design for a chance type amusement device, substantially as shown and described.
